United States Patent

Des. 241,723
Patented Oct. 5, 1976

241,723

BASKET

Ewing L. Sharp, North Hollywood, Calif.
(1014 W. Burbank Blvd., Burbank, Calif. 91506)

Filed Jan. 2, 1975, Ser. No. 538,135

Term of patent 14 years

Int. Cl. D9—04

U.S. Cl. D9—247

FIG. 1.

FIG. 2.

FIG. 4.

FIG. 1 is a side elevational view of a basket embodying my new design;

FIG. 2 is a front elevational view thereof;

FIG. 3 is a top plan view thereof; and

FIG. 4 is another side elevation view thereof illustrating the basket in a partially open configuration.

I claim:

The ornamental design for a basket, as shown.
